METHOD OF EMBALMING DEAD BODIES

Hilton Ira Jones, Wilmette, Ill., and Robert L.
St. Pierre, Indianapolis, Ind.

Application August 15, 1933, Serial No. 685,282

2 Claims. (Cl. 27—22)

This invention relates to an apparatus and a method of embalming dead bodies.

An object of the invention is the provision of a process for embalming bodies in which the body is placed in a confined space and subjected to either a vacuum or pressure, or both, in connection with a sterilizing fluid.

Another object of the invention is the provision of a process for embalming bodies in which the body is placed in a confined space so that after the blood vessels have been drained of their contents an embalming fluid may be injected intravenously after which the body may be covered with the embalming fluid and pressure and a vacuum may be alternately applied to the confined space so that the embalming fluid may be forced inwardly and withdrawn through the tissues of the body so that all parts of the body will be affected by the fluid.

A still further object of the invention is the provision of a tank or container having a slidably mounted tray therein for receiving the dead body, the tank being provided with an air-tight seal so that a vacuum may be produced in the container or pressure is created for applying the embalming fluid to all parts of the body, the container being provided with tubes which are adapted to be connected with the veins and arteries for draining the same and for supplying said veins and arteries with embalming fluid as is well known.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a side elevation of an apparatus constructed in accordance with the principles of our invention,

Figure 2 is a top plan view with parts broken away,

Figure 3 is a front end view with parts broken away showing the interior of the apparatus, and

Figure 4 is a transverse vertical section taken along the line 4—4 of Figure 1.

Referring more particularly to the drawings, 18 designates a base member which is supported by standards 11 and 12. These standards are so constructed at their upper ends as to support a cylindrical tank or container 13.

This tank is provided with windows 14 which are sealed to openings in the top wall of the tank in order to create an air-tight compartment within the tank. A drain 15 is located at one end of the tank and on the bottom and is normally closed by a plug 16. The drain is only employed for removing any liquids remaining in the tank after the embalming process has been completed. The drain may also be employed for cleansing the interior of the apparatus.

One end of the cylindrical tank is open as shown at 20 but is normally closed. A circular angle iron member 21 is secured to the outer wall of the tank adjacent the opening 20 in any approved manner to provide a laterally disposed flange 22 which is provided with slots 23 to receive headed bolts 24. Nuts 25 are threaded onto the outer ends of the bolts for sealing a flange 26 of a cover 27 to the flange 22. The cover plate is provided with laterally projecting arms 30 having journals 31 adapted to be aligned with journals 32 formed at the ends of the arms 33 which are secured to the side wall of the container. A pintle 34 is received by the journals 31 and 32 thus forming a hinged mounting for the cover or door 27.

The interior of the container is provided with a pair of tracks 35 which are secured in any approved manner to the inner wall of the container and these tracks are adapted to support rollers 36. A tray 37 which is curved is adapted to receive the body to be embalmed and the tracks extend substantially the full length of the container so that the tray 37 may be moved inwardly or outwardly of the container after the door 27 has been opened. Blocks 38 are secured at spaced points upon the underface of the tray 37 and axles 39 are threaded at 40 into the blocks. The tray is provided with a curved flange 41 and adjacent the axles 39 are provided passages to receive the axles so that the axles are supported by the blocks 38 and the flange 41.

Projecting into the container 13 at spaced points are a pair of metal tubes 45 and 46. These tubes are provided with a nipple 48 to which is adapted to be attached a rubber tube 49. This tube as shown in Fig. 3 is adapted to be extended to the body and inserted into a vein or artery as the case may be. Any number of these tubes may be employed for the purpose. As shown at 50 in Figure 1, the free ends of these tubes 45 and 46 project beyond the wall of the container and are adapted to be connected with a device for supplying an embalming fluid for intravenous injection.

A pipe 52 extends from an air pump 53 up

around the outer wall of the container 13 and enters the top of the container, as shown at 56. A pipe 55 enters the container as shown at 54 at the top and extends downwardly to the air 5 pump 53. A valve 57 is interpolated in the pipe 52 and is adapted to cut off this pipe from the interior of the tank or container 13. A pipe 58 is provided with a valve 59 which is connected with the pipe 52 between the valve 57 and the 10 air pump 53 and is adapted to supply the pump with air when desired. A valve 60 is adapted to cut off communication between the tank 13, the pipe 55 and the air pump 53. A pipe 61 is connected with the pipe 55 between the valve 60 15 and the air pump 53 and is provided with a valve 62 adapted to close the pipe 61 to the atmosphere. A motor 63 drives the pump 53 through a shaft 64.

The motor 63 by means of a shaft 65 drives 20 a fluid pump 66. This pump is connected by a pipe 67 having a valve 68 with a source of fluid, not shown. A pipe 69 connects the pipe 67 with the bottom of the tank 13 and is controlled by a valve 70.

25 A pipe 71 connects the pump 66 with the storage tank containing an embalming fluid and is adapted to provide means for supplying the pump with the embalming fluid while the pipe 67 returns the fluid to the storage tank. A valve 72 30 controls the flow of the fluid to the pump. A pipe 73 connects the pipe 71 with the bottom of the tank 13 and is a discharge pipe for the fluid which has been supplied to the tank. A valve 74 controls the flow of the fluid from the 35 tank.

A pressure gage 75 is connected with the top of the tank while a vacuum gage 76 is connected with the top of the tank 13 and located adjacent the pressure gage 75.

40 In carrying out my method for embalming dead bodies in the tank 13 the body is placed upon the tray 37 and is securely fastened thereto. The tubes 49 which may be of any number are connected with the veins and arteries so that the 45 vascular system may be drained in the usual manner by connecting the outer ends 50 of the pipes 45 and 46 with some form of pump. The pipes may then be connected with a storage tank and an embalming fluid pumped into the vascular 50 system. In certain cases, the embalming fluid may be pumped into the tank 13 through the inlet pipe 69 until the body is covered with the same. The valves 60 and 61 of the associated 55 air pump 53 in Figure 4 are then closed while the valves 57 and 59 are opened and the pump will force air through the pipe 52 and into the chamber in the tank 13 until the desired pressure is registered in the gage 75 and this pressure is maintained for a predetermined period so that 60 the embalming fluid will be forced from the exterior of the body to the interior.

65 After the fluid has been drained from the chamber 13 the valves 60 and 62 are opened to permit the escape of air. The valve 59 is then closed while the valve 57 is maintained open. The pump operating in this manner will create a vacuum in the tank 13 so that the fluids which have been forced into the body by the air pressure and also the fluid which has been forced 70 into the vascular system will be drawn outwardly through the tissues of the body so that all parts of the body will be properly affected by the embalming fluid. The operation just described, including a series of steps of supplying 75 the tank with fluid, applying pressure to the fluid,

removing the fluid and then creating a vacuum in the tank may be repeated until the embalming process has been completed.

It will be appreciated that any type of fluid 5 may be employed for embalming bodies such as gaseous disinfectants and certain of these disinfectants may be formaldehyde, sulphur dioxide and the like. The disinfectants may be applied singly or in combination.

The thorough penetration of all the tissues of 10 the body is what is accomplished by this method.

The circulatory system of the body may be drained of the normal body fluids and then injected with the embalming fluid while the body is in the tank and when a pressure or vacuum has been applied to the tank. During the injection 15 of the embalming fluid into the vascular system the body may be subjected to a pressure of formaldehyde and sulphur dioxide gases.

The tank may also be employed for dehydrating 20 bodies where the bodies contain an excess of water in such cases as dropsy and in those bodies where drowning has occurred. In this case dry air is admitted after a vacuum has been maintained in the tank.

25 This method of embalming the body is particularly efficacious in those cases where the body has been mutilated by an accident or by necropsy. In such cases where mutilation has been such that it is impossible to drain the blood vessels, 30 the dismembered portions of the body may be placed on the tray and alternately subjected to vacuum and pressure in connection with the embalming fluids so that the embalming fluids will be forced through the tissues and withdrawn so that the 35 tissues will be thoroughly saturated. When the mutilated body and the parts are placed on the tray they are first subjected to a vacuum in order to remove blood and air from the tanks. After the body has been in a high vacuum for some 40 time air is allowed to enter and very considerable pressure is maintained on the parts. The embalming fluid, however, is maintained about the body and the parts so that the tissues will be thoroughly saturated.

45 Not only may human bodies be embalmed as has been described above, but the tank may be employed for curing meats, such as hams, bacon, and the like. Ordinarily the hams, for example, are soaked in a strong solution of sodium nitrate, 50 to which some sugar has been added. After the saturation is complete, the hams are dried and smoked. The saturation process requires a great deal of time and this time may be considerably reduced by employing the alternate vacuum and 55 pressure method described above for causing saturation of the meats with the sodium nitrate solution.

We claim:

1. The method of embalming bodies that have 60 their vascular systems drained which comprises confining a body in a restricted space, injecting an antiseptic fluid into the vascular system, enveloping the body in an antiseptic fluid in the 65 confined space, creating for predetermined periods alternately pressures and vacuums in the confined space for alternately forcing the antiseptic fluid through the tissues to the interior of the body and for withdrawing through the tissues a portion of the antiseptic fluid thus forced 70 into the body and also some of the antiseptic fluid from the vascular system until the tissues of the body are thoroughly saturated with the fluid, the antiseptic fluid being withdrawn from the space before the periods of vacuum. 75

2. The method of embalming bodies that have their vascular systems drained which comprises confining a body in a space sealed against the atmosphere, injecting an antiseptic fluid into the 5 vascular system, creating a vacuum in the space for withdrawing fluids from the body, supplying an antiseptic fluid to the space to completely envelop the body with said antiseptic fluid, then creating a pressure in the space and maintaining 10 the pressure on the antiseptic fluid to force the same into the tissues of the body, remov-

ing the envelop of the antiseptic fluid and creating a vacuum in the space for a predetermined time and until the antiseptic fluid in the vascular system is drawn outwardly from the interior of the body and through the tissues, supplying the 5 confined space with the withdrawn fluid and applying alternate pressures and vacuum to the space until the tissues of the body have become saturated with the fluid.
